UNITED STATES PATENT OFFICE.

WILLIAM HAAKER, OF VERONA, NEW JERSEY.

VACUUM-RECEPTACLE COVER.

No. 860,743.

Specification of Letters Patent.

Patented July 23, 1907.

Application filed May 15, 1906. Serial No. 316,959.

To all whom it may concern:

Be it known that I, WILLIAM HAAKER, a citizen of the United States, residing at Verona, in the county of Essex and State of New Jersey, have invented certain new and useful Improvements in Vacuum-Receptacle Covers, of which the following is a specification, reference being had therein to the accompanying drawing, in which—

Figure 1 is a vertical sectional view showing the cover applied to a receptacle in the form of an ordinary drinking glass; Fig. 2 a plan view of the cover; Fig. 3 a vertical sectional view of a slightly different form of the cover; and Fig. 4 a plan view of the cover shown in Fig. 3.

15 One of the many objects of this invention is to provide a simple and effective cover for vacuum storage receptacles, and which is provided with means whereby it may be readily punctured in order to admit air into the receptacle and thereby release the cover.

20 A further object of the invention is to provide such a cover which may be used in connection with an ordinary drinking glass or tumbler.

A further object of the invention is to provide such a cover with a push-button-like device carrying a 25 puncturing pin by which the cover may be perforated to admit air into the receptacle; and to so form the cover that the push-device will be so protected that it will be practically impossible to accidentally force it inward. The push-device is so located in the cover 30 that the receptacle may be packed, one upon another, without the least danger of forcing the puncturing pin through the cover.

Referring to the various parts by numerals, 1 designates the cover proper which is provided on its under 35 side near its edge with an annular channel 2. In this channel I prefer to run melted plastic material of any suitable character which when cold will adhere to the walls of said channel and form an elastic packing ring 3. I prefer to melt the elastic material and run it into the 40 channel in a fluid state for the reason that I thereby obtain an absolutely air-tight joint between the elastic material and the walls of the channel which receives it, and at the same time securely fasten the elastic ring within the channel. It is manifest that where a separate packing-ring of rubber, or similar material, is placed in this channel that it is difficult to secure an air tight connection between the rubber ring and the walls of the channel, thereby requiring an unnecessarily heavy pressure on the cover to maintain the air tight connection with the receptacle.

As shown in Fig. 1, I provide the cover with a central depression or well 4, the bottom of which is slightly above the lower edge of the annular flange 5 around the edge of the cover, said flange 5 forming one wall of the

channel 2. In this well is placed an inverted cup-like 55 push-device 6, the lower edge of said device resting on the bottom of the well or depression. The upper edge of the side wall of the well is turned over on the top of the push-device 6 and serves to retain said device within the well. The top of the push-device bulges 60 slightly upward, as shown clearly in Fig. 1, but its upper surface does not project above the upper edge of the side wall of the well or depression, so that said wall forms an annular protecting wall for said push-device. To the under side of the upper wall of the 65 push device is secured a downward extending puncturing pin 7, said puncturing pin terminating slightly above the bottom of the well.

When it is desired to release the cover from the receptacle the upper wall of the push-device is forced downward, preferably by pressing the thumb thereon, and the puncturing pin driven through the bottom wall of the well. This permits air to pass into the receptacle and thereby releases the cover.

It will, of course, be understood, that the joint between the upper edge of the side wall of the well and the upper edge of the push device is not air-tight, so that air may pass down through said joint and into the receptacle through the aperture made therein by the puncturing-pin.

It is, of course, manifest that the push-device or puncturing-pin may be secured to the cover in a great variety of ways. In Fig. 2 the puncturing pin 7^a is secured to a push-plate 6^a, this plate 6^a being located in a central depression or well 5^a formed in the cover. It will be 85 noted that in this construction the push-device is below the upper surface of the main part of the cover so that it will not be accidentally depressed. The plate 6^a is secured in place by a drop of solder on the tongue 6^b.

By locating the puncturing device in a depression in 90 the cover, and protecting it, substantially as described, the receptacles may be placed one upon another in a packing case without any danger of the pins being forced through the covers. It will also be noted that the push-devices are so protected that they will not be accidentally broken from the covers. This is particularly so in the construction shown in Figs. 1 and 2.

From the foregoing it will be seen that I provide a cover for a vacuum receptacle with a permanently attached puncturing-device; and that said device is so 100 protected it will be practically impossible to accidentally force the puncturing pin through the cover. By providing a cover of this construction it will be extremely simple to detach the cover of a vacuum jar, at the same time avoiding the necessity of procuring a 105 sharp pointed instrument and a hammer, as is now necessary, in order to remove the ordinary vacuum jar cover.

Having thus described my invention, what I claim as new and desire to secure by Letters Patent, is:—

1. A cover for a vacuum receptacle formed with a depression or well in its upper side, a push-device located in said depression, the upper edge of the wall of said depression being turned over to retain the push-device in place and to serve as a protection therefor, and a puncturing pin carried by the push-device and adapted to be forced through the bottom of the depression.
- 10 2. A cover for a vacuum receptacle provided with an annular channel or groove in its under side near its edge containing elastic packing material and adapted to receive the edge of a receptacle, the main body of the cover being depressed below the upper wall of said channel or groove, whereby said wall will protect the main body of the cover, said main body being formed with a depressed well, and a push device located in said well and carrying a puncturing pin, the upper wall of said well extending above the push device but below the upper edge of the wall of the channel

or groove, whereby the push device will be protected by 20 the wall and accidental puncturing of the cover will be prevented.

3. A vacuum receptacle cover formed with an annular groove on its under side near its edge adapted to contain elastic sealing material and to receive the edge of a receptacle, the main body of the cover being depressed below the upper wall of said groove and formed with a depressed well, a push device located in said well and below the upper wall thereof, and a puncturing pin carrier by said push device, whereby the upper wall of the annular groove 30 will protect the body of the cover and the upper edge of the wall of the well will protect the push device and prevent accidental puncturing of the cover.

In testimony whereof I hereunto affix my signature in the presence of two witnesses this 14th day of May 1906. 35

WILLIAM HAAKER.
